UNITED STATES PATENT OFFICE

FRANK B. JENNINGS, OF DAYTON, OHIO

DESIGN FOR AN INDIVIDUAL PIPE TRAY

Application filed April 10, 1928. Serial No. 26,216. Term of patent 3½ years.

To all whom to may concern:

Be it known that I, FRANK B. JENNINGS, a citizen of the United States, residing at Dayton, in the county of Montgomery, and State of Ohio, have invented a new, original, and ornamental design for an Individual Pipe Tray, of which the following is a specification, reference being had to the accompanying drawing, forming part hereof.

I claim:

The ornamental design for an individual pipe tray, as shown.

FRANK B. JENNINGS.
